[57] CLAIM

The ornamental design for a clip for mounting a decorative light bracket on a roof or similar planar support surface, as shown.

DESCRIPTION

FIG. 1 is a side elevational view of a clip for mounting a decorative light bracket on a roof or similar planar support surface showing my new design;

FIG. 2 is a front elevational view thereof;

FIG. 3 is a top plan view thereof;

FIG. 4 is a rear elevational view thereof;

FIG. 5 is an inverted opposite side elevational view thereof;

FIG. 6 is a bottom plan view thereof; and,

FIG. 7 is a top perspective view thereof.

FIG. 1

FIG. 2

FIG. 3

FIG. 4

FIG. 5

FIG. 6

FIG. 7
